UNITED STATES PATENT OFFICE.

GEORGE W. HOLLAND, OF GREENVILLE, SOUTH CAROLINA.

SHUTTLE-BOX.

1,233,234.

Specification of Letters Patent. Patented July 10, 1917.

Application filed April 13, 1916. Serial No. 90,993.

To all whom it may concern:

Be it known that I, GEORGE W. HOLLAND, a citizen of the United States, residing at Greenville, in the county of Greenville and State of South Carolina, have invented certain new and useful Improvements in Shuttle-Boxes, of which the following is a specification.

The present invention relates to weaving, and more particularly to new and useful improvements in shuttle-boxes.

The primary object of my invention is to provide a shuttle-box having improved means thereon for mounting the binders, whereby to facilitate renewal of the binder bearing without discarding the whole box.

Other objects and advantages to be derived from the use of my improved shuttle-box will appear from the following detail description and the claim, taken with an inspection of the accompanying drawings, in which—

Figure 1 is a perspective view of a shuttle-box embodying the improvements of my invention, and

Fig. 2 is a detail perspective view of the renewable bearing member of my invention.

Referring more particularly to the drawings, wherein similar characters of reference designate like and corresponding parts throughout the various views, 1 designates in its entirety a shuttle-box of the usual construction being formed of cast metal and having a plurality of compartments formed by the partitions or sides 2. The box is provided with the usual end flanges 3 for guiding purposes and is formed with a plurality of spaced lugs 4. The binders are designated 5 and may be of the usual construction having the free ends thereof movable between the lugs 4, a pin 6 extending transversely through said lugs serving to limit the movement of said binders.

The structure described above is embodied in the usual form of shuttle-box now used. I have found that in actual practice the most vulnerable part of the present type of the shuttle-boxes is the bearing provided for the binders. This bearing is usually formed integral with the shuttle-box and should the bearing become worn or injured in any way, the whole box is rendered useless. My invention contemplates the provision of an improved bearing member for detachable association with a shuttle-box of the class described, and may be placed on

the original box when manufactured, or may be used for repairing the shuttle-boxes now in use.

My improved bearing includes a body portion 7 having a pair of openings 8 therein for reception of screws 9 or the like for securing the bearing to the shuttle-box, the base portion 10 of the shuttle-box being employed for this purpose, as best shown in Fig. 1. The body portion 7 of my improved bearing is provided with a plurality of relatively spaced laterally extending lugs 11 provided with alining openings 12. The hub portion 13 of the binders 5 are receivable between the lugs 11 and a bearing pin 14 is arranged therethrough. The lower edges 15 of the lugs 11 are preferably straight so as to lie flush on the base portion 10 of the box. The usual flat springs 16 mounted at 17 on the base portion 10 are supplied, such springs having their free ends in operative engagement with the binders 5 as indicated at 18.

My invention is primarily designed as a bearing renewing device for shuttle-boxes now in use, it being, of course, necessary that the old wornout bearing be removed from the box when replacing the same with my improved bearing. I also intend to supply my improved bearing for shuttle-boxes when the latter are originally manufactured.

The shuttle-box illustrated in the drawings is of the usual multicellular construction and contains but two compartments, but it will be obvious that any number of compartments might be employed with a corresponding number of binders, in which event my improved bearing would be enlarged for use in this connection. The operation of the shuttle-box need not be described since this is well known to those skilled in the art.

From the above description taken in connection with the accompanying drawings, it is thought that a clear and comprehensive understanding of the construction, operation and advantages of my invention may be had, and while I have shown and described my invention as embodying a specific structure, I desire that it be understood that I may make such changes on said structure as do not depart from the spirit and scope of the invention as described.

What I claim as new and desire to secure by Letters Patent is:

The combination with a shuttle box, of a

detachable mounting for the binders of the shuttle comprising a longitudinal bar, a plurality of bearings extending from the bar and at right angles to the same, said bearings being relatively large at their forward ends, a pin extending through the enlarged ends of the bearings adjacent their upper

edges, the under faces of the bearings being flat, and a plurality of binders loosely engaged with the pin.

In testimony whereof I affix my signature¹³ hereto.

GEORGE W. HOLLAND.
